ATTORNEYS

UNITED STATES PATENT OFFICE.

ABBOTT COBURN, OF CHICAGO, ILLINOIS.

SHINGLE CONSTRUCTION.

Application filed January 31, 1927. Serial No. 164,965.

My invention relates to shingle construction, and it consists in the combinations, constructions, and arrangements herein described and claimed.

5 In the past few years roofing manufacturers have had considerable trouble from the curling of the so-called asphalt composition shingles. This curling may result from unequal expansion or contraction of the 10 shingle due to extremes of heat or cold, as well as to the action of the elements, such as the formation of ice or the force of the wind.

Various attempts have been made to prevent the curling of shingles of this type.

15 To this end certain shingles have been provided with a tongue which is arranged to enter a slot in an adjacent shingle. This has to an extent prevented the curling of the shingle, but the trouble is that the tongue, 20 itself, is liable to curl.

An object of my invention is to provide a composition shingle construction in which there is provided a tongue for locking the shingle in position and thereby preventing 25 curling, while at the same time keeping the tongue, itself, in a locked position and thus making a smooth roof structure.

Another object is to provide a composition shingle in which the tongues and slots are so arranged that they may be readily interlocked with a minimum of labor.

Other objects and advantages will appear in the following specification, and the novel features of the invention will be particularly 35 pointed out in the appended claims.

My invention is illustrated in the accompanying drawings, forming part of this application, in which

40 Figure 1 is a plan view of a shingle formed according to my invention,

Figure 2 is a plan view, showing a portion of the arrangement of a plurality of shingles on the roof, and

45 Figure 3 is an enlarged section along the line 3-3 of Figure 2, showing the manner in which the shingles are locked.

In carrying out my invention, I make use of a composition shingle of a standard type. This may be the so-called asphalt 50 shingle which may consist of layers of felt, asphalt and crushed slate or other suitable material, the invention residing not in the material of which the shingle is made, but rather in the means for preventing the curling of the shingles.

In Figure 1 I have shown a shingle of the

preferred form. This consists of a body portion 1 having forwardly projecting portions 2 which are separated by a recess 3, a recess 4 being provided near one corner of the 60 shingle. The projecting portions 2 each has a pair of slots 5 and 6, respectively, which are disposed near the edge of the extensions 2 and are preferably located centrally of said extensions. Tongues 7 are punched from 65 the shingle, extending inwardly from the inner edges of the recesses 3 and 4. These tongues, as it will be observed, are connected at their inner ends to the body portion of the shingle. 70

From the foregoing description of the various parts of the device, the operation thereof may be readily understood. In Figure 2 I have shown a number of the shingles as they have been applied to the roof. Assuming that the line $a-a$ at the bottom of Figure 2 represents the edge of the roof, it will be observed that I have cut off the extensions 2 of the first row of shingles so that the shingles present a straight edge 80 along said roof edge. The shingles are laid end to end, and, as will be observed, the extensions are staggered so that they overlap. The tongues 7 of the first row of shingles are inserted through the slots 5 85 and are then passed through the slots 6.

The next row of shingles is staggered likewise and their tongues 7 are passed through the slots 5 and 6 in the same manner. As each additional row of shingles is 90 laid, the tongues are locked in the slots, and it will be observed that the end of the tongue is always beneath the exposed part of the shingle. Of course each row of shingles is nailed before the next row is laid on, this 95 nailing being done at the points 8, which, as will be observed, are near the tongues 7. When the next adjacent row of shingles is laid, these nail holes of course are covered.

When the roof is finally shingled, it will 100 present the appearance shown in Figure 2. It will be noted that the tongues 7 are firmly secured and lie underneath the exposed portion of the shingle. This forms a very substantial and thoroughly locked 105 shingle covering. There are no exposed parts which are liable to curl because they are virtually locked in place by the tongue and slot arrangement.

I claim:

1. A composition roofing, comprising a series of rows of shingles, each of said

shingles having a body portion and spaced-apart extensions, each of said extensions having a pair of parallel slots disposed centrally thereof, and said body portion being 5 provided with a tongue at the edge of the space between said extensions, the extensions of the shingles of one row being staggered with respect to the extensions of the shingles of the other row and the tongues of one row 10 of shingles being arranged to pass upwardly through certain of the parallel slots and downwardly through other of the parallel slots and to lie underneath and be covered by the extensions bearing the slots.

15 2. A composition roofing comprising a series of rows of shingles, each of said shingles having a body portion and spaced-

apart extensions, each of said extensions having a pair of parallel slots disposed centrally thereof and in close proximity with 20 respect to each other, and said body portion being provided with a tongue at the edge of the space between said extensions, the extensions of the shingles of one row being staggered with respect to the extensions of the shingles of the other row and the tongues of 25 one row of shingles being arranged to pass upwardly through certain of the parallel slots and downwardly through other of the parallel slots and to lie underneath and be 30 covered by the extensions bearing the slots, whereby the tongues will lockingly hold the extensions in place.

ABBOTT COBURN.
